INVENTOR

BY *Robert B. Billings*
ATTORNEY

UNITED STATES PATENT OFFICE.

ANGELOS KOMNENUS, OF NEW YORK, N. Y., ASSIGNOR OF ONE-HALF TO ELIZA O'DAY,
OF DEAL, NEW JERSEY.

WRENCH.

Application filed February 23, 1922. Serial No. 538,663.

To all whom it may concern:

Be it known that I, ANGELOS KOMNENUS, a subject of the King of Greece (who has declared his intention to become a citizen of the United States), residing at New York city, in the county of New York and State of New York, have invented certain new and useful Improvements in Wrenches, of which the following is a specification.

10 My invention relates to improvements in wrenches and it is my object to provide the Robert wrench of U. S. Patent No. 1,407,578, dated February 21, 1922, with means whereby it will easily and quickly engage a pipe 15 or other object and which will freely release it after the pipe has been screwed home.

It was found in practical use that the Robert wrench would not easily engage a pipe, especially in confined spaces and that 20 once engaged it could not be released except by the application of great force and that it let go suddenly and violently and generally struck and injured nearby objects. When used on the end of an extension it was al- 25 most impossible to engage or release it.

I have overcome these difficulties in the manner illustrated in the accompanying drawing in which Fig. 1 is a side view of my improved form of the Robert wrench with 30 the jaws closed; Fig. 2 a top view of the structure of Fig. 1; and Fig. 3 a side view with the jaws engaging a pipe.

The Robert wrench, as made and sold, comprises a handle 1 with an integral jaw 35 2 and a co-operating jaw 3 connected to the jaw 2 by links 4—4 and 5—5 secured to the jaws by pins 6, 6, 6, 6. These links are non-parallel, the pins on the jaw 3 being further apart than those on the jaw 2. Neither are 40 the links of equal length, the link 5 at the rear being longer than the link 4. A spring 7 connects the links and tends to draw the jaws together, their closing movement being limited by a stop 8 on the jaw 2.

45 When the wrench was to be engaged with a pipe or other object the jaw 3 had to be laid against one side thereof and the jaws forced apart by pressure on the handle against the tension of the spring 7, which 50 was very hard to do at arm's length. When

the wrench was to be removed a reverse pressure had to be applied to the handle and at the same time it had to be pulled rearwardly but the toothed jaws were held to the pipe by the spring pressure and considerable force 55 had to be applied whereupon it slipped and let go suddenly generally knocking a hole in the plaster or otherwise injuring nearby objects.

I have overcome all these difficulties by 60 providing the jaw 3 with a rearwardly extending finger piece 9 which preferably terminates in a hook 10 lying close to the handle 1. This enables a workman to place his forefinger or thumb of the hand holding the 65 wrench on the finger piece and by a slight rearward pull to open the jaws to any desired extent to engage a pipe or other object. When the wrench is to be removed a slight rearward pull on the finger piece 70 opens the jaws and enables the wrench to be easily removed.

When the wrench is used on the end of an extension (a short piece of pipe being generally used for this purpose) to enable otherwise inaccessible places to be reached a piece 75 of wire or string can be fastened to the hook 10 and the jaws quickly and easily opened or closed.

I do not limit myself to the finger piece 80 and hook shown and described as others may be employed to give the same result but that shown has been found in practice to be the best form for one hand operation of the wrench.

85 I claim:—

1. A pipe wrench comprising a handle and integral jaw, a co-operating jaw, non-parallel links of unequal length connecting said jaws, a spring tending to pull the jaws together and a finger piece extending rearwardly along the handle from the co-operating jaw.

2. A pipe wrench as set forth in claim 1 in combination with a hook-like extension on 95 the end of the finger piece.

In testimony wherof I have affixed my signature.

ANGELOS KOMNENUS.
